UNITED STATES PATENT OFFICE.

GEORGE M. MACDONALD, OF SAN BERNARDINO, CALIFORNIA.

ARTIFICIAL HONEYCOMB AND THE ART OF AND MEANS FOR MAKING THE SAME.

1,383,650.

Specification of Letters Patent. Patented July 5, 1921.

Application filed July 19, 1920. Serial No. 397,429.

To all whom it may concern:

Be it known that I, GEORGE M. MACDONALD, a citizen of the United States, residing at San Bernardino, in the county of 5 San Bernardino and State of California, have invented new and useful Improvements in Artificial Honeycombs and the Art of and Means for Making the Same, of which the following is a specification.

10 This invention relates more particularly to improvements upon and in the art of making the type of honeycomb described in my previous Patent No. 1,224,479, issued May 1, 1917.

15 This type of honeycomb is composed of a plurality of superimposed thin strips, each being crimped to form a series of transverse grooves alternately arranged upon opposite sides of the strip and extending outwardly 20 from each side of the longitudinal center thereof. Each of these grooves forms a semi-cell which is open at its outer end and practically closed at its inner end and when the strips are super-imposed the semi-cells of 25 one strip register with those of the adjacent strips to form complete cells open at their outer ends and practically closed at their inner ends.

The principal object of this invention is to 30 provide a construction and a method of making the same whereby the various component elements may be most cheaply constructed and quickly, accurately and rigidly assembled. It also provides all of the advantages 35 pointed out in the above mentioned previous patent, viz, an indestructible honeycomb which may be used a great many times, and from which the honey may be easily extracted by centrifugal or other means and which 40 may be easily and thoroughly cleaned and sterilized, which is especially desirable in case it becomes infected, infested or diseased as sometimes happens.

The invention comprises the ribbon, and 45 the combination by which the comb is formed.

The device is further provided with other novel and advantageous features of construction and arrangement as will be hereinafter 50 more fully described and particularly pointed out in the claims.

The ribbon may be of any suitable material adapted to the purpose and which will not be obnoxious or repellent to the bees. At present I make said ribbon of very thin 55 sheet aluminum but I do not limit myself to the use of aluminum or other metal.

Other objects, advantages and features of invention may appear from the accompanying drawing, the subjoined detail description 60 and the appended claims.

The accompanying drawing illustrates the invention.

Figure 1 is a fragmental side elevation of a honeycomb constructed in accordance with 65 this invention.

Fig. 2 is an enlarged perspective of a portion of the crimped metallic ribbon which forms the cells.

Fig. 3 is an enlarged fragmental perspective of said crimped ribbon bent upon itself to form substantially two superimposed strips, semi-cells of one strip registering with semi-cells of the other to form complete cells. 75

Fig. 4 is a transverse section on line x^4-x^4 , Fig. 3, showing more particularly the burs and binding rod or wire.

Fig. 5 is a fragmental longitudinal mid-section of a ribbon and comprises parts of 80 three strips before the ribbon is folded.

1 represents the frame, rectangular in shape and preferably made of wood, projecting lugs 2 being provided at its upper end by which it is supported in the bee hive, not 85 shown.

3 represents the metallic strips, a plurality of which being crimped and superimposed and mounted within the frame, form the cells that constitute the honeycomb. The strips 3, 90 preferably made of very thin sheet aluminum or other suitable material are formed integrally of a continuous ribbon of such material; the strips being joined one to the other, end to end, by flat uncrimped bent 95 portions 4 of the material.

Each strip is crimped to form transverse grooves 5 alternately disposed upon opposite sides of the strip and alternately arranged upon opposite sides of the longitudinal axis thereof. Each groove so formed constitutes a semi-cell, preferably semi-hex-

agonal in shape, being open at the ends at the edges of the strips and practically closed at their bottom at the center of the strips by the wall 6 formed of the material of the 5 strips.

The ribbon is provided at the junctions of the strips; that is to say, at the middles of the uncrimped portions 4, respectively, with narrow transverse slots *a*, the walls *b* of 10 which slots extend in the form of burs projecting from the faces of the ribbon, first on one side and then on the other; the ribbon being continuous and unbroken from end to end; there being integral marginal 15 portions *c*, of the ribbon between the ribbon edges and the ends of said slots.

The narrow slots *a* serve to locate and determine the line of the bend *d*; and the projecting burs serve to maintain the ribbon 20 unrumpled.

The strips are superimposed within the frame by folding the ribbon at the middles of the blank spaces 4 and extending the 25 strips, one upon the other, from edge to edge of the frame and when so superimposed the semi-cells of the strips respectively register with those of adjacent strips and form complete hexagonal cells open at the edges of the strips and practically closed 30 at the center of the strips.

The strips are held in proper relative position and retained within the frame by wires 7 which extend through holes 8 in the strips and also through holes 8', 8'' in the bottom 35 and top members of the frame, the ends 7', 7'' of the wires being bent into recesses 9, 9' in the frame to hold said wires in place. The holes 8 are preferably punched in the strips at the time they are crimped and are 40 similarly located in each strip relative to its ends and grooves so that when they are caused to register in arranging the strips, the semi-cells will also accurately register with each other.

45 The holes 8 for each strip are punched from the side of the ribbon opposite that from which the holes for the adjoining strips are punched. This is done before the ribbon is folded to form the superimposed strips so that the burs 10 formed by punching the holes will extend from opposite sides of successive strips respectively before the ribbon is folded; and after the ribbon is folded and the strips are superimposed upon 50 each other, said burs will all extend in the same directions from edge to edge of the body formed by the folded ribbon. This arrangement will allow the end 7'' of the rod 7, before said end is bent over, to be 55 easily passed through the holes without being caught upon the burs; after which the end is bent as shown.

It will be seen that the strips can be rapidly formed of a continuous ribbon of the

requisite material by passing it between die 65 rollers or like means which will crimp and punch it as hereinbefore described. The wooden frames are cheaply constructed and the strips may be quickly folded at the blank portions 4 and placed in superimposed relation in the frame, the semi-cells being accurately registered by passing the wires through the holes 8; the wires also binding the superimposed strips together and holding 70 them in the frame. 75

A sufficient number of the strips will be placed in each frame to completely fill the space between the top and bottom members thereof, being thus pressed and held in close contact and not requiring any other joining 80 means.

The honeycomb thus formed is dipped into melted wax which forms a coating on the walls of the cells and it is then hung by its projecting lugs 2 in the bee-hive to be filled 85 with honey by the bees; after which the comb may be removed from the hive and the honey expelled by centrifugal or other means, and other wax coating applied and the honeycomb replaced in the hive to be 90 filled again.

I claim:

1. An artificial honeycomb comprising a plurality of strips having grooves therein; 95 said strips being integrally formed end to end and folded to assume superimposed positions relative to each other, the said grooves registering with similar grooves in adjacent strips to form complete cells.

2. An artificial honeycomb comprising a 100 plurality of strips formed of a continuous ribbon of sheet material constructed to form transverse grooves and uncrimped portions of the material between each two crimped strips; said ribbon being folded with the 105 strips superimposed upon each other and the grooves of each strip in register with similar grooves in adjacent strips to form cells.

3. An artificial honeycomb comprising a 110 plurality of strips formed integrally of a continuous ribbon of sheet material crimped to form transverse grooves alternately disposed on opposite sides of the strips and alternately extending from each side of the 115 longitudinal center of the strip; said grooves being open at the edges of the strips and practically closed at the center thereof; there being uncrimped portions of the material between and joining each two strips and folded so that the strips are superimposed upon each other and the grooves of one strip register with similar grooves in adjacent strips to form complete cells. 120

4. An artificial honeycomb comprising a 125 frame; a plurality of strips formed integrally end to end of a continuous ribbon of sheet material folded so that the strips

are superimposed upon each other; said strips respectively having grooves that register with similar grooves in adjacent strips to form cells, and means for retaining said strips in closely related superimposed position in said frame.

5. An artificial honeycomb comprising a plurality of strips formed integrally end to end of a continuous ribbon of sheet material 10 folded to superimposed positions relative to each other, said strips respectively having grooves to register with similar grooves in adjacent strips to form cells; said strips also having holes located similarly in each strip 15 relative to its ends and grooves, and rods extending through said holes to bind the strips in superimposed relation and to register the grooves.

6. An artificial honeycomb comprising a 20 frame, a plurality of strips integrally formed end to end and folded to superimposed positions relative to each other; said strips having grooves to register with similar grooves in adjacent strips to form cells 25 and said strips also having holes located similarly in each strip relative to its ends and grooves; and wires extending through holes in said frame and through the holes in the strips to hold the strips in superimposed relation in the frame and to register the grooves with each other.

7. An artificial honeycomb comprising a plurality of strips integrally formed end to end and adapted to be folded at the junction 35 between their ends to assume superimposed positions relative to each other; said strips having grooves to register with similar grooves in adjacent strips to form cells, and said strips also having holes 40 punched and located similarly in each strip relative to its ends and grooves; the burs formed by punching said holes occurring alternately on opposite sides of each successive strip before the strips are folded, and 45 all extending in one direction when the strips are folded and superimposed; and wires extending through said holes to bind the strips in superimposed relation and to register the grooves with each other.

50 8. An artificial honeycomb comprising a frame, a plurality of elongated strips integrally formed end to end of sheet material and crimped to form transverse grooves alternately disposed upon opposite sides of the 55 strips and alternately extending from opposite sides of the longitudinal center, being open at the edges of the strips and practically closed at the center thereof; said strips also having holes punched and similarly located in each strip relative to its ends 60 and grooves, and the burs formed by punching said holes occurring alternately on opposite sides of each successive strip before the ribbon is folded, and all extending in

one direction after the ribbon is folded and superimposed; there being uncrimped portions at the ends of the strips so that the strips are superimposed on each other and the grooves of said strip register with similar grooves in adjacent strips to form cells; 70 and wires extending through holes in the frame and through the holes in the strips to hold the strips in superimposed relation in the frame and to register the grooves with each other.

75 9. The method set forth of making metallic honeycomb which consists in crimping a metallic ribbon to form a series of semi-cell crimps in pre-determined lengths with blank spaces between said series; then punching 80 the crimped spaces alternately, one series being punched in one direction and the next series in the other direction, so that the burs formed by the punch will be reversely arranged upon the successive strips; then folding the ribbon upon itself to bring the holes into register with each other, with the burs all in one direction, and then inserting wires through said holes in the direction of the burs and securing said strips in a frame by 90 means of said wires.

10. A ribbon of material adapted to form an artificial honeycomb crimped to form transverse grooves alternately disposed upon opposite sides to form semi-cells open at the 95 edges of the strips and practically closed at the center of the strips by walls formed of the material of the strips; said ribbon being provided with uncrimped portions with narrow transverse slots to locate bends whereby the strips may be accurately brought together to cause the crimps to register to form complete cells.

100 11. A ribbon of material adapted to form an artificial honeycomb crimped to form transverse grooves alternately disposed upon opposite sides to form semi-cells open at the edges of the strips and practically closed at the center of the strips by walls formed of the material of the strips; said ribbon being provided with uncrimped portions with narrow transverse slots to locate bands whereby the strips may be accurately brought together to cause the crimps to register to form complete cells; said slots being 110 formed with burs which give rigidity to the ribbon so that the ribbon will not be crimped by the operation of bending the same.

115 12. A ribbon crimped to form a honeycomb structure and provided with transverse slots adapted and arranged to facilitate bending the ribbon in the process of forming the honeycomb.

120 13. A ribbon crimped to form a honeycomb structure and provided with transverse slots adapted and arranged to facilitate bending the ribbon in the process of

forming the honeycomb; said slots having burs adapted to prevent crimping of the ribbon during the process of bending.

14. A ribbon crimped to form a honeycomb structure and provided with transverse slots adapted and arranged to facilitate bending the ribbon in the process of forming the honeycomb; said slots having burs extending transversely of the ribbon, upon

that side of said ribbon which will be outside when the ribbon is bent to form the honeycomb.

In testimony whereof I have hereunto set my hand at Los Angeles, California, this 12th day of July, 1920.

GEORGE M. MACDONALD.
